Primary Examiner—Ted Shooman*Assistant Examiner*—Mitchell I. Siegel*Attorney, Agent, or Firm*—Tilton, Fallon, Lungmus & Chestnut**[57] CLAIM**

The ornamental design for a golf putter head, as shown and described.

DESCRIPTION

FIG. 1 is a perspective view of a golf putter head embodying my new design;

FIG. 2 is a front elevational view of the golf putter head shown in FIG. 1;

FIG. 3 is a heel end elevational view of the golf putter head shown in FIG. 1;

FIG. 4 is a rear elevational view of the golf putter head shown in FIG. 1;

FIG. 5 is a toe end elevational view of the golf putter head shown in FIG. 1;

FIG. 6 is a top plan view of the golf putter head shown in FIG. 1;

FIG. 7 is a bottom plan view of the golf putter head shown in FIG. 1;

FIG. 8 is a bottom plan view of a second embodiment of the golf club head as disclosed in FIG. 1; and,

FIG. 9 is a bottom plan view of a third embodiment of the golf club head as disclosed in FIG. 1.

The broken line showing of fragmented shaft in FIG. 1 is for illustrative purposes only and forms no part of the claimed design.

The undisclosed sides of the second and third embodiments are identical to those disclosed in FIGS. 1-6.
